Application June 1, 1946, Serial No. 673,748

12 Claims. (Cl. 250—95)

1

The present invention relates to what is known in the art as a phototimer which is used primarily with photo-fluoroscopic apparatus.

This latter apparatus is now quite extensively employed by the roentgenologist where it is desired to radiographically examine a large group of persons or objects in a short period of time. Instead of taking direct individual radiographic exposures with the time required to change films, the X-rays are passed through the object being radiographed on to a fluorescent screen, as in normal fluoroscopy. A photographic exposure utilizing continuous motion picture film is then made of the image cast on the fluorescent screen thus making a permanent record of the object, to be followed by another with a minimum lapse of time.

Inasmuch as the objects vary in thickness, the quality of the photographic exposure depends on the intensity of the fluoroscopic image appearing on the screen, with the latter in turn being determined by the kilovoltage, milliamperage, and time of energization of the X-ray tube. For the purpose of assuring reasonable uniformity in resultant photographs the phototimer was developed which operates to de-energize the X-ray tube when the image appearing on the fluorescent screen has reached a predetermined intensity.

Certain inherent disadvantages are, however, found in prior art phototimers. For example, when the image appearing on the fluorescent screen reaches the desired intensity, there is a certain time delay before the system responds and de-energizes the X-ray tube, which frequently has heretofore resulted in over-exposure of the photographic film with attendant loss in diagnostic value. In addition, prior art phototimers have made no provision to protect the X-ray tube nor other costly parts of the system in the event that it fails to function in its normal intended manner. Moreover, with prior art phototimers there has been no way of ascertaining whether or not there is a failure of a given exposure and the latter could not be determined until after development of the film.

It is accordingly an object of the present invention to provide a phototimer wherein the X-ray tube is de-energized without any substantial time delay upon the photographic image reaching the desired intensity.

Another object of the present invention is the provision of a phototimer wherein protective devices are provided to prevent damage or destruction to the X-ray tube and other elements in the

2

event of failure of operation of the phototimer for various reasons.

Another object of the present invention is the provision of a phototimer wherein an indication is provided for the purpose of signalling to the operator the failure of a given exposure.

Still further objects of the present invention will become obvious to those skilled in the art by reference to the accompanying drawing where-
10 in the single figure is a schematic illustration of a phototimer constructed in accordance with the present invention.

Referring now to the drawing in detail, the phototimer of the present invention comprises a
15 rectifier power supply chassis shown within the dashed frame 5, a photo-camera chassis shown within the dashed frame 6, and the X-ray tube excitation circuit illustrated to the right of the dashed frames 5 and 6. The photo-camera chassis 6 fastens to a photofluorographic hood 7, provided with a fluorescent screen 8, against which a patient or object 9 rests, and at the converging end of the hood a 35 or 70 millimeter camera
20 10 is secured, in the manner shown in the upper left hand portion of the drawing. Due to the position of the photo-camera chassis, light from the fluorescent screen 8 is directed by a lens 12, provided in the wall of a casing 13, on to the photosensitive cathode 14 of a multiplier phototube 15.

Referring now to the various elements contained within the photo-camera chassis 6, it will be noted that the cathode 14 of the phototube 15 connects to a terminal 16 on the chassis 6, while its output anode 17 is connected by means of a manually operable switch 18, a fixed resistance 19, and contacts 20 of a relay 22, to another terminal 23 on the photo-camera chassis 6. Also, within the chassis 6 is a photofluoroscopic timing condenser 24 connected across the contacts
30 20 of relay 22, as well as a radiographic timing condenser 25 connected across additional contacts 26 of relay 22 for a purpose hereinafter described.

40 The multiplier phototube 15 is of the well known type and since its various multiplying dynodes are supplied with a difference of potential of increasing magnitude therebetween, a high resistance 27 is connected, by a manually operable switch 28, a doubly variable resistance 29 for initial "calibration" and "density control" and fixed resistance 30 across the chassis terminal 16 and 23, with the various multiplying electrodes tapped to points on the resistance 27. A 45 glow relay tube 32 is also housed within the

photo-camera chassis 6 which has one of its main electrodes connected to one side of the photo-fluoroscopic timing condenser 24 while its starting electrode is connected through a fixed resistance 33, switch 18, and fixed resistance 19, to the opposite plate of condenser 24. The remaining main electrode of the glow relay tube 32 is connected to a chassis terminal 34 and in a similar manner the winding of relay 22 is connected to a pair of chassis terminals 35 and 36.

The advantage of housing all of the above mentioned elements within the photo-camera chassis 6 resides in the fact that leakage losses are minimized and high capacitance due to a long multiple conductor cable is reduced. Thus only a five conductor cable, all of which carry only control current, is required between the photo-camera chassis 6 and the rectifier power supply chassis 5 and all conductors carrying low values of current for operation of the photo-tube 15 and glow relay tube 32 are of relatively short length.

Referring now more particularly to the rectifier power supply chassis 5, it will be noted that the latter houses a transformer 40, the primary winding 42 of which is connected, by means of conductors 43 and 44 and a variable resistance 45 of about 1000 ohms, to taps of an auto-transformer 46 forming part of the X-ray tube energizing unit, so that the primary winding 42 is immediately energized upon closure of the main line switch (not shown) normally employing to connect the auto-transformer to a source of the customary commercial supply of 195 to 250 volts. The high voltage secondary winding 47 of transformer 40 is arranged to supply approximately 1150 volts D. C. which constitutes the input source for the photo-camera chassis 6.

To this end one side of the secondary winding 47 is connected, by a conductor 48, to a rectifier chassis terminal 49 and photo-camera terminal 16, and from the latter to the cathode of phototube 15, so that when conducting the path will be completed from the anode 17, through switch 18 and resistance 19, to one plate of timing capacitor 24. The opposite end of secondary winding 47 is connected to the anode of a half-wave rectifying valve tube 50, with the thermionic cathode of the latter being connected, by a "common" conductor 52 to a rectifier chassis terminal 53, thence to photo-camera chassis terminal 23 and thus to the remaining plate of timing capacitor 24, and being grounded at G.

It will be noted that the primary winding 42 of high voltage transformer 40 is shunted by a grid glow tube 54 having its main electrodes connected to the respective line conductors 43 and 44 through variable resistance 45, while its control electrode is connected through a resistance 55 of approximately 20,000 ohms to the line conductor 43. This tube 54 operates as a voltage stabilizer and passes current during the portion of the alternating current cycle that the half-wave rectifier tube 50 is also conducting, the primary winding 42 being properly phased for this purpose. Thus in passing current the control electrode of tube 54 is momentarily positive with respect to the cathode and current flow between the main electrodes causes a voltage drop in the resistance 45.

As the input line voltage varies, the amount of current taken by the tube 54 in shunt with the primary winding 42 likewise varies. When the voltage increases the current through tube 54 varies and causes an additional voltage drop in the resistance 45 which thus absorbs the effect of

line voltage fluctuations resulting in the voltage across the primary winding 42 remaining substantially constant. The higher ohmic resistance 55 is employed to limit the flow of grid current during each impulse which results in more stable operation of the tube 54.

Accordingly, since the transformer 40 is energized by a constant voltage, the secondary winding 47 will charge the timing capacitor 24 at a uniform rate in direct proportion to the light falling or phototube 15, once the normally grounded condition of the anode of phototube 15 is removed by opening of the contacts 20 and 26 of relay 22. This results from the fact that one or the other of the variable resistances 29 is selectively in circuit, depending upon the position of switch 28. The amount of resistance set at 29 determines the voltage biasing the ninth dynode of multiplier phototube 15 with respect to the eighth dynode, thus controlling the gain of the multiplier phototube and so the exposure density.

It will also be noted that the variable resistance 29 forms part of the divider network, comprising resistances 21, 29 and 30, across the high voltage supply transformer 40, tube 50, and the low voltage cathode heating source for tube 50. Consequently, a change in the resistance 29 will vary the voltage between the eighth and ninth dynodes of the multiplier phototube 15 whereas such change in the resistance 29 will have little effect on the voltage across these other elements. A filtering capacitor 56 is connected across the rectified high voltage from secondary winding 47 resulting in a voltage of approximately 1200 volts between the chassis terminals 16 and 49 to ground.

For the purpose of interrupting the X-ray tube energizing circuit when the image appearing on the fluorescent screen 8 has reached the desired intensity, as well as to protect the X-ray tube in the event of failure of the phototimer and to give a signal of such failure, the rectifier chassis 5 houses various elements among which is an additional transformer 57 having its primary winding 58 connected to the conductors 43 and 44 and thus to taps on the auto-transformer 46, in the same manner as primary winding 42 of high tension transformer 40.

The secondary winding 59 has its ends connected to the respective ends of a full-wave rectifying valve tube 60 while its mid-point is connected to the "common" conductor 52 and thus to ground at G. The transformer 57 is also provided with a low voltage winding 61 for supplying heating energy to the thermionic cathode of half-wave rectifier 50 and a variable resistance 62 of about 100,000 ohms is connected between the center tap of winding 61 and the "positive" leg of the high voltage supply or "common" conductor 52. Adjustment of resistance 62 causes large variations in the value of the high voltage supply and allows for calibrating the equipment for constant densities with large variations in multiplier phototube outputs.

65 A similar low tension winding 63 also supplies heating energy to the thermionic cathode of full-wave rectifier 60. A D. C. relay 64 has one end of its winding connected by a conductor 65 to the cathode of rectifier 60 while its remaining end is connected through a resistance 66 of 35,000 ohms to "common" conductor 52 and thus to the mid-point of secondary winding 59 from which the relay is energized whenever transformer 57 and rectifier tube 60 are energized and functioning properly. On the other hand, should the low

voltage power supply (i. e., tube 60 and transformer 57) fail for any reason, relay 64 will not operate and an X-ray exposure cannot therefore be initiated.

Shunted across the winding of D. C. relay 64 and resistance 66 is a series connected voltage regulator tube 67 and resistance 68 of about 15,000 ohms which forms a voltage regulator or "protective circuit," as it will be hereinafter referred to, for a purpose later herein explained. A capacitor 69 shunts the tube 67 and resistance 68, by having one of its plates connected to the "common" conductor 52 and its other plate connected to the conductor 65, and operates to smooth out rectified pulsations produced by the windings 59 and 63 of transformer 57, and tube 60, to more nearly approximate a direct current.

A relay 70 is provided with a pair of normally closed contacts 72 which in the de-energized position of the relay connects one plate of a safety timing condenser 73 through an adjustable resistance 74 and thence by a conductor 75, contacts 72, and a conductor 76, to "common" conductor 52, while the remaining plate of condenser 73 is directly connected to "common" conductor 52. This accordingly causes condenser 73 to discharge through resistance 74 each time the relay 70 is de-energized thus resetting the safety timer to an initial state of practically no charge at the inception of each exposure.

Relay 70 is provided with a pair of normally open contacts 77, one of which is connected by a conductor 78 to a point between tube 67 and resistance 68 and it will be noted that conductor 75 also connects to one end of the winding of a relay 79 and to one end of the winding of a further relay 80. The relay 79 is provided with a pair of normally closed contacts 82 and a pair of normally open contacts 83, while the relay 80 has a single pair of normally closed contacts 84.

As shown, the X-ray tube excitation circuit is controlled by a pair of relays 85 and 86, with the relay 85 provided with a pair of normally open contacts 87 and the relay 86 having a pair of normally open contacts 88 and 89. Since one end of the primary winding 90 of a high tension transformer 91 is connected directly to a tap of the auto-transformer 46, closure of contacts 89 of relay 86 will connect the remaining end of primary winding 90 to a further voltage tap on the auto-transformer 46 through a resistance 92. The simultaneous closure of contacts 88 of relay 86 completes an energizing circuit to the winding of relay 85, as hereinafter explained, which causes closure of its contacts 87 thus short-circuiting the major portion of the resistance 92, employed merely to absorb the sudden rush of current due to relay 86 operating slightly prior to that of relay 85.

Upon energization of the primary winding 90 of transformer 91, the secondary winding 93 thereof supplies unidirectional energy to the X-ray tube 94 through a high voltage rectifier bridge arrangement 95 with the current being measured on a milliammeter 96 connected to a rectifier bridge circuit 97 in well known manner.

The contacts of the various relays, as above noted, are employed to operate control circuits. Although all of the relays, with the exception of relays 64, 79 and 80, are energized from an alternating current source, for the sake of simplicity in describing the control circuits, it will be assumed that at a given moment the A. C. supply source has a positive and negative polarity. Ac-

cordingly, supply conductor 43 will be assumed as the negative and conductor 44 as positive.

As shown conductor 43 extends to normally open contacts 98 of D. C. relay 64, so that upon closure thereof a negative polarity will be supplied by a conductor 99 to one end of the winding of relay 70. Since a conductor 100 is connected to conductor 43 and extends to one side of a signal alarm 102, such as a bell, buzzer, lamp or the like, and a conductor 103 is also connected to the conductor 99 and extends, through a rectifier chassis terminal 104 and photo-camera chassis terminal 36, to one end of the winding of relay 22, a negative polarity is thus supplied to the windings of both relays 22 and 70 upon closure of relay contacts 98 while the signal alarm 102 receives a negative polarity independent of contacts 98. A negative polarity is also supplied from the supply conductor 43 directly to the windings of relays 85 and 86 by a conductor 105.

The positive conductor 44 is connected to the "exposure switch" 106 which upon closure extends this positive polarity through a conductor 107 to a junction 108. From the latter a conductor 109 extends to a rectifier chassis terminal 110 and photo-camera chassis 35 and thus to the other end of the winding of relay 22 and since a conductor 112 connects to the conductor 109 and to the other end of the winding of relay 70, a positive polarity is thus supplied to both relays 22 and 70, upon closure of "exposure switch" 106. Also extending from the junction 108 is a conductor 113 which connects to one of a further pair of normally open contacts 114 provided on relay 70. From the other contact of this pair 114 a conductor 115 extends to the normally closed contacts 84 of relay 80, and through such contacts 84, by means of a conductor 116, to the normally closed contacts 82 of relay 79, thence by a conductor 117 to the other end of the winding of relay 86. Thus the energization of this latter relay 86, which initiates an X-ray exposure, is dependent upon the closure of "exposure switch" 106 and also closure of contacts 114 of relay 70. A conductor 118 connects the other side of the signal alarm 102 to one of the normally open contacts 83 of relay 79.

It will be noted that the other end of the winding of D. C. relay 80 is connected by a conductor 119 to a rectifier chassis terminal 120 and thus to photo-camera chassis terminal 34 and the remaining end of the winding of relay 79 is connected to one of the main electrodes of a glow relay tube 122 with the other main electrode of this tube being connected to "common" D. C. supply conductor 52. The safety timing condenser 73 is also connected through a resistance 123 of about 10,000 ohms to the control electrode of the glow relay tube 122.

The operation of the photo-timer of the present invention is as follows: the main line switch (not shown) is first closed thus energizing the auto-transformer 46. The latter in turn energizes the primary windings 42 and 58 of the respective transformers 40 and 57 with the former being supplied with a substantially constant voltage by operation of voltage regulator tube 54 in the manner previously described. Energization of transformer 42 causes the secondary winding 47 thereof to charge filtering capacitor 56 and supply current for the divider network comprising the resistances 27, 29 and 30 at this time, since the phototube 15 is non-conductive as no light is falling on its cathode, due to the fact the X-ray

tube 94 is not yet energizing and hence no image appears on the fluorescent screen 8.

However, energization of transformer 57 causes its low tension windings 61 and 63 to heat the thermionic cathodes of the respective rectifier tubes 50 and 60 and the secondary winding 59 to energize the winding of relay 64, through a circuit extending from the mid-point of transformer 59 through negative or "common" conductor 52, resistance 66, to winding of relay 64 and hence through conductor 65 and rectifier tube 60 to one or the other ends of secondary winding 59 during alternate half-waves of the alternating current cycle. At the same time capacitor 69 is charged by secondary winding 59.

The winding of D. C. relay 64 thus becomes energized immediately upon the filament of rectifier tube 60 reaching electron emitting temperature and closes its normally open contacts 93. Closure of the latter merely conditions the control circuits for operation since no circuits are completed by contacts 98 but "negative" polarity from the conductor 43 is supplied to one end of the windings of relays 22 and 70, by the conductors 99, and 103. Also "negative" polarity is supplied directly to one side of the signal alarm 102 by conductor 100.

The doubly variable resistance 29 in the photo-camera chassis having been set for the desired calibration and density of film, a patient or object 9 is positioned in front of the fluorescent screen 8 carried at the front of the camera-hood, ready for an exposure. The operator then closes the "exposure switch" 106. This completes a circuit from positive supply conductor 44 through conductor 107, junction 108, and conductors 109 and 112, terminals 113 and 35, to the other end of the windings of both relays 22 and 70, and thence through conductors 99 and 103 and the now closed contacts 98 of relay 64 back to negative supply conductor 43. Energization of relay 70 opens the discharge circuit for safety timing condenser 73 at the contacts 72 and causes closure of its normally open contacts 77 and 114. Closure of contacts 114 completes a circuit from the junction 108, through conductor 113, now closed contacts 114, conductor 115, normally closed contacts 84 of relay 80, conductor 116, normally closed contacts 82 of relay 79, conductor 117 to winding of relay 86 and back to line conductor 43 through conductor 105.

The relay 86 is thus energized and closes its normally open contacts 88 and 89. Closure of contacts 89 according energizes high tension transformer 91 through resistance 92, and closure of contacts 88 energizes the winding of relay 85 with attendant closure of its normally open contacts 87, which short circuits the major portion of resistance 92 after but an instant following operation of relay 86. The X-ray tube 94 accordingly is energized and generates X-rays which are directed toward the object 9.

The energization of relay 22 simultaneously with relay 70, as above noted, causes the normally closed contacts 20 and 26 of relay 22 to open thus removing the grounded condition of timing capacitors 24 and 25. The closure of normally open contacts 77 of relay 70 connects the conductor 78 to the conductor 75 which thus supplies a positive side of the control voltage from the transformer 59 to one end of each of the windings of relays 79 and 80, but since the negative side is at this time interrupted neither of these latter relays are as yet energized.

Upon the appearance of an image on the fluo-

rescent screen 8, due to the passage of X-rays from the now energized X-ray tube 94, the light from such image passes through the lens 12 and falls upon the cathode 14 of phototube 15. Since transformer 40 was previously energized upon closure of the main line switch, the secondary winding 47 thereof now charges timing capacitor 24 at a rate directly proportional to the light falling on the phototube 15, through a circuit extending from one end of secondary winding 47, through conductor 48 and chassis terminals 49 and 16, to the cathode 14 of phototube 15. From the anode 17 the circuit then extends through switch 18, resistance 19 to one side of capacitor 24 and thence from the other plate thereof, through chassis terminals 23 and 53, negative or "common" conductor 52 and rectifier tube 50, to the other end of secondary winding 47.

When capacitor 24 has become charged to a value equal to the triggering voltage of the glow relay tube 32 at a rate dependent upon the light falling upon the phototube 15 the voltage thereof is impressed through current limiting resistance 33 across one of the main electrodes and the control electrode of glow relay tube 32. As is characteristic of this type tube, a discharge occurs between the latter two electrodes when the triggering voltage is reached which ionizes the gas within the tube causing a discharge to occur between the two main electrodes. Breakdown of this tube 32 accordingly completes a circuit extending from the mid-point of secondary winding 59, through negative or "common" conductor 52, chassis terminals 53 and 23, tube 32, chassis terminals 34 and 120, conductor 119, winding of D. C. relay 80, conductor 75, now closed contacts 77 of relay 70, conductor 78, resistance 68, and conductor 65 through rectifier tube 60 back to one or the other ends of secondary winding 59.

Relay 80 is accordingly energized by the unidirectional energy from winding 59 and opens its normally closed contacts 84. Opening of these latter contacts 84 thus interrupts the control circuit causing de-energization of relays 70, 85 and 86 with a cessation in the generation of X-rays from the X-ray tube 94 due to opening of relay contacts 87, 88 and 89. Release of the exposure switch 106 allows opening of contacts 77 of relay 70 to interrupt the D. C. source of supply for relay 80 allowing it to again close its normally closed contacts to condition the control circuit for making another photo-fluorograph upon closure of the "exposure switch" 106. At the same time closure of the normally closed contacts 72 of relay 70 again connects the safety timing condenser 73 in series with the resistance 74 allowing the condenser 73 to completely discharge, thereby resetting the safety timer.

It can accordingly be seen that upon the timing condenser 24 becoming completely charged at a rate dependent upon the light falling on the multiplier phototube 15 and under control of the doubly variable resistance 29, the X-ray tube 94 is immediately de-energized when the image appearing on the screen 8 is of the desired pre-selected density to assure a proper film exposure. Moreover, the resistance 19 in series with the timing condenser 24 functions as a compensating arrangement to allow for the X-ray "on" contactor drop-out time, namely relay 86 and its contacts 88 and 89. It has been found that this drop-out time is of the order of 1.2 cycles, and in order to prevent an over-exposure must be compensated for which is one of the salient features of the present invention.

As previously mentioned the current through phototube 15 varies in proportion to the intensity of the light emitted from the fluorescent screen 8 within the hood 7. Thus the timing condenser 24 charges up to a given voltage in a time proportional to light intensity and reaches this given voltage when the same quantity of light has fallen upon the phototube cathode 17. The condenser 24 accordingly reaches a voltage sufficient to trigger glow relay tube 32 and terminate the exposure when a given amount of light (controlled by density control resistance 29) is emitted by fluorescent screen 8. However, since the drop-out time for contacts 88 and 89 of relay 86 requires 1.2 cycles this additional time of energization of the X-ray tube 94 actually adds to the exposure before it is finally terminated. With a long exposure of .3 second (18 cycles), this additional 1.2 cycle exposure means only a 6.7% over-exposure which is short enough as to be disregarded since it produces no serious results to the film. However, on a short exposure of .05 second (3 cycles), which is within the range of a large percentage of exposures, this additional 1.2 cycles of relay drop-out time means a 40% over-exposure that is serious since it results in faulty films.

In order to produce films of a consistent density with varying exposure times, the compensating resistance 19 is utilized, since with the latter in circuit, the voltage drop across the compensating resistance varies directly with phototube output current, and the glow relay tube 32 triggers when a given total voltage is reached across the compensating resistance 19 and timing condenser 24. Accordingly, the condenser 24 needs to charge only to the difference of the given total triggering voltage necessary and the voltage appearing across the compensating resistance 19. Inasmuch as the voltage across the compensating resistance 19 varies inversely with the time of exposure, consistent film densities are obtained at varying exposure times.

In addition to the compensating arrangement the present invention provides a protective circuit which suppresses voltage surges and also protects the X-ray tube from injury by overloading or the like. As above noted, relay 64 and resistance 66 comprise a protective circuit which prevents operation of the apparatus should the low voltage power supply, consisting of transformer 57 and rectifier 60, fail for any reason. If this failure should occur during the making of an exposure it would be impossible for the timing tube 32 and the safety timing tube 122 to ionize and operate relays 79 or 80, either of which terminates the exposure. By placing relay 70, which initiates the exposure, under control of relay 64, the exposure is terminated upon failure of the low voltage power supply, even though relays 79 and 80 fail to operate because their respective control tubes 122 and 32 do not become conductive, and of course if the power supply has failed prior to the making of an exposure then relay 64 cannot initially operate.

Since transformer 57 has its primary winding 58 connected to the auto-transformer supply conductors 43 and 44, it is possible for the output potential from secondary winding 59 to vary and impress a varying anode potential on tubes 32 and 122 which effects their ignition thus resulting in inconsistent timing. In order to stabilize the low voltage power supply, the voltage regulator tube 67 and resistance 68 is provided,

so that if the output voltage of the low voltage power supply increases, the current taken by tube 67 increases. This increase in tube current causes an increase in the voltage drop in resistance 68 which subtracts from the output voltage of the low voltage power supply.

On the other hand, if the output voltage decreases, the current through tube 67 will likewise decrease and the voltage drop in resistance 68 will decrease thus adding to the output voltage of the low voltage power supply. Thus the voltage across tube 67 remains substantially constant and since the voltage for timing tube 32 and safety timing tube 122 is taken directly across tube 67, the ignition potential of tubes 32 and 122 remains constant. The condenser 69, as before mentioned, is utilized to smooth out the pulsations so that the rectified low voltage power supply more closely approximates a true D. C. source.

The safety time circuit comprising condenser 73, variable resistance 117 and glow relay tube 122 together with fixed resistance 123 and relay 73 is provided to terminate an exposure after the lapse of a definite period of time in the event the timing circuit, which should operate in response to light falling on the phototube 15, fails for any reason to so operate. Upon operation of relay 70, in the manner previously explained to initiate an exposure, safety-timing condenser 73 is charged during the same period that main timing condenser 24 is being charged through phototube 15.

This charging circuit extends from conductor 35 75 (now carrying a positive polarity from transformer 57 through conductor 65, resistance 68, conductor 78 and closed contacts 71 of relay 70) through variable resistance 74 to condenser 73 and thence to the negative or "common" conductor 52. Resistance 74 is adjusted to regulate current flow and thus the time required to charge condenser 73 which is made comparable to that normally required to charge main timing condenser 24 but so that the latter normally operates to terminate the exposure whereas safety timing condenser 73 operates to terminate the exposure only when a safe period of time elapses and condenser 24 fails to operate.

Upon condenser 73 becoming charged to the triggering potential of glow relay tube 122 the latter becomes conductive thus completing the circuit from negative or "common" conductor 52 through tube 122 to winding of relay 79 and thence to conductor 75 carrying a positive polarity from the lower voltage power supply source. This accordingly energizes relay 79, causing opening of its normally closed contacts 82 included in the X-ray exposure control circuit previously traced, and terminating the exposure in the same manner as contacts 84 of relay 80 would have terminated the exposure had this latter relay become energized since relay contacts 82 and 84 are in series.

This operation of relay 79 also closes normally open contacts 83 thus completing a circuit to the signal alarm 102 so long as the exposure switch 106 is closed which indicates to the operator that the safety timing circuit, or "time limit," terminated the exposure, instead of the main timing or "phototimer" circuit. Such audible indicator advises the operator that either the X-ray tube or phototube has failed for some reason, or that the kilovoltage preset for the particular patient or object being radiographed,

11

was too low resulting in an exposure which is longer than safe tube rating.

The present invention also provides for the photo-timing of 14 in. x 17 in. radiographs with consistent film densities. In making radiographs a film cassette containing intensifying screens within the film cassette is positioned on the hood 7 in front of the fluorescent screen 8. A shutter 124 provided in the hood 7 is rotated by a handle or crank 125 from its normally horizontal position, as shown in full line, to a vertical position, as shown in dotted lines, in front of the camera shutter. Although shown schematically in the drawing, rotation of this shutter to the vertical position also moves switches 18 and 28 within the photo-camera chassis from their respective full line positions to that shown in dotted lines and, though not shown, the circuit to the camera motor is also interrupted by movement of the shutter 124.

Movement of switch 18 cuts timing condenser 24 and compensating resistance 19 out of circuit and cuts in timing condenser 25 and a further series connected compensating resistance 126. In a similar manner switch 28 cuts out of circuit the doubly variable resistance or density control 29 and cuts in a similar density control doubly variable resistance 127, which thus conditions the entire apparatus for operation to take a 14" x 17" radiograph, in the same manner as previously described for the making of a photo-fluorographic exposure.

The necessity for a change in certain elements is due to the fact that the intensifying screens within the film cassette are usually of a different type of fluorescent screen than the screen 8 within the hood 7, and hence the X-ray film receives light from a different type screen than that from which the phototube 15 receives light, namely, screen 8. Consequently, because of the response differences of the screens, film and phototube, it is necessary to utilize a compensating resistance 126 and timing condenser 25, as well as a doubly variable resistance 127, of a somewhat different order of magnitude than used for photofluoroscopy. However, by selecting the proper value for the combination of timing condenser 25 and compensating resistance 126 and with a desired setting of the density control resistance 127, 14" x 17" radiographs of consistent density are obtainable with a single X-ray tube, kilovoltage and milliamperage for various patient or object thicknesses. When the shutter 124 is returned to its normally horizontal position the apparatus is again set for photofluoroscopy.

It thus becomes obvious to those skilled in the art that a phototimer is herein provided which accurately and automatically operates to terminate either a radiographic or photofluorographic exposure to insure consistent film densities with patients of varying thicknesses, or for varying exposure times. Also compensation is made for the time required for various instrumentalities to operate to terminate such exposure so that the apparatus operates accurately in response to truly desired film density and not to any pseudo-density which includes operation time of other circuit elements. Moreover, the phototimer of the present invention incorporates a protective arrangement preventing injury to the X-ray tube and voltage regulating of the various tubes to insure consistent operation under all conditions. Furthermore, an audible indicator is provided to advise the operator when certain undesirable operating conditions of the apparatus exist.

12

Although one specific embodiment of the present invention has been shown and described, it is to be understood that still further modifications thereof may be made without departing from the spirit and scope of the appended claims.

We claim:

1. A phototimer for automatically controlling energization of an X-ray tube to consistently produce radiographic images of uniform density regardless of variations in object thicknesses or varying exposure times comprising energizing means for said X-ray tube, control means responsive to initiation by an operator adapted to automatically cause operation of said X-ray tube energizing means, protective means including a substantially constant voltage power supply and a relay energizable therefrom and operable to partially complete a circuit to said control means and serving in event of power supply failure to prevent operation of said control means with otherwise attendant possible injury to the X-ray tube, and intensity responsive means automatically operable to cause cessation in the operation of said X-ray tube energizing means when the radiographic image produced by passage of X-rays through an object on to a light sensitive surface reaches a predetermined density.

2. A phototimer for automatically controlling energization of an X-ray tube to consistently produce radiographic images of uniform density regardless of variations in object thicknesses or varying exposure times comprising energizing means for said X-ray tube, control means responsive to initiation by an operator adapted to automatically cause operation of said X-ray tube energizing means including a plurality of relays whose contacts normally close a partial circuit to said control means, protective means including a substantially constant voltage power supply and a relay energizable therefrom and operable to partially complete a circuit to the windings of the relays of said control means and serving in event of power supply failure to prevent operation of said control means with otherwise attendant possible injury to the X-ray tube, and intensity responsive means automatically operable to complete the partially completed circuit to the winding of one of the relays of said control means to render the latter effective to cause a cessation in the operation of said X-ray tube energizing means when the radiographic image produced by passage of X-rays through an object on to a light sensitive surface reaches a predetermined density.

3. A phototimer for automatically controlling energization of an X-ray tube to consistently produce radiographic images of uniform density regardless of variations in object thicknesses or varying exposure times comprising energizing means for said X-ray tube, control means responsive to initiation by an operator adapted to automatically cause operation of said X-ray tube energizing means, protective means operable to condition said control means for operation and operable in event of power supply failure to prevent operation of said control means with otherwise attendant possible injury to the X-ray tube, intensity responsive means automatically operable to cause a cessation in the operation of said X-ray tube energizing means when the radiographic image produced by passage of X-rays through an object on to a light sensitive surface reaches a predetermined density, and compensating means connected to said intensity responsive means and operable to compensate for the time delay re-

quired for said X-ray tube energizing means to cease operation in response to operation of said intensity responsive means to prevent an over-exposure and assure density uniformity of the radiographic image.

4. A phototimer for automatically controlling energization of an X-ray tube to consistently produce radiographic images of uniform density regardless of variations in object thicknesses or varying exposure times comprising energizing means for said X-ray tube, control means responsive to initiation by an operator adapted to automatically cause operation of said X-ray tube energizing means, intensity responsive means automatically operable to cause a cessation in the operation of said X-ray tube energizing means when the radiographic image produced by passage of X-rays through an object on to a light sensitive surface reaches a predetermined density, and safety timer means automatically operable to cause a cessation in the operation of said X-ray tube energizing means after the lapse of a preselected period of time in the event said intensity responsive means fails to operate and terminate the X-ray exposure.

5. A phototimer for automatically controlling energization of an X-ray tube to consistently produce radiographic images of uniform density regardless of variations in object thicknesses or varying exposure times comprising energizing means for said X-ray tube, control means responsive to initiation by an operator adapted to automatically cause operation of said X-ray tube energizing means, intensity responsive means automatically operable to cause a cessation in the operation of said X-ray tube energizing means when the radiographic image produced by passage of X-rays through an object on to a light sensitive surface reaches a predetermined density, and safety timer means including a capacitor adapted to be charged over a preselected period of time simultaneously with operation of said intensity responsive means, and automatically operable to cause a cessation in the operation of said X-ray tube energizing means after the lapse of such preselected period of time in the event said intensity responsive means fails to operate and terminate the X-ray exposure.

6. A phototimer for automatically controlling energization of an X-ray tube to consistently produce radiographic images of uniform density regardless of variations in object thicknesses or varying exposure times comprising energizing means for said X-ray tube, control means responsive to initiation by an operator adapted to automatically cause operation of said X-ray tube energizing means, intensity responsive means automatically operable to cause a cessation in the operation of said X-ray tube energizing means when the radiographic image produced by passage of X-rays through an object on to a light sensitive surface reaches a predetermined density, safety timer means automatically operable to cause a cessation in the operation of said X-ray tube energizing means after the lapse of a preselected period of time in the event said intensity responsive means fails to operate and terminate the X-ray exposure, and an indicator operable in response to operation of said safety timer means to apprise the operator that the safety timer means and not the intensity responsive means terminated the X-ray exposure.

7. A phototimer for automatically controlling energization of an X-ray tube to consistently produce radiographic images of uniform density

regardless of variations in object thicknesses or varying exposure times comprising energizing means for said X-ray tube, control means responsive to initiation by an operator adapted to automatically cause operation of said X-ray tube energizing means, intensity responsive means automatically operable to cause a cessation in the operation of said X-ray tube energizing means when the radiographic image produced by passage of X-rays through an object on to a light sensitive surface reaches a predetermined density, safety timer means including a capacitor adapted to be charged over a preselected period of time simultaneously with operation of said intensity responsive means and automatically operable to cause a cessation in the operation of said X-ray tube energizing means after the lapse of such preselected period of time in the event said intensity responsive means fails to operate and terminate the X-ray exposure, and an indicator operable in response to operation of said safety timer means to apprise the operator that the safety timer means and not the intensity responsive means terminated the exposure.

25 8. A phototimer for automatically controlling energization of an X-ray tube to consistently produce radiographic images of uniform density regardless of variations in object thicknesses or varying exposure times comprising energizing means for said X-ray tube, control means responsive to initiation by an operator adapted to automatically cause operation of said X-ray tube energizing means, protective means operable to condition said control means for operation and serving in event of power supply failure to prevent operation of said control means with otherwise attendant possible injury to the X-ray tube, intensity responsive means automatically operable to cause a cessation in the operation of said X-ray tube energizing means when the radiographic image produced by passage of X-rays through an object on to a light sensitive surface reaches a predetermined density, safety timer means automatically operable to cause a cessation in the operation of said X-ray tube energizing means after the lapse of a preselected period of time in the event said intensity responsive means fails to operate and terminate the X-ray exposure, and an indicator operable in response to operation of said safety timer means to apprise the operator that the safety timer means and not the intensity responsive means terminated the X-ray exposure.

55 9. A phototimer for automatically controlling energization of an X-ray tube to consistently produce radiographic images of uniform density regardless of variations in object thicknesses or varying exposure times comprising energizing means for said X-ray tube, control means responsive to initiation by an operator adapted to automatically cause operation of said X-ray tube energizing means including a plurality of relays whose contacts normally close a partial circuit to said control means, protective means including a substantially constant voltage power supply and a relay energizable therefrom and operable to partially complete a circuit to the windings of the relays of said control means and serving in event of power supply failure to prevent operation of said control means with otherwise attendant possible injury to the X-ray tube, intensity responsive means including a circuit having a capacitor therein adapted to be charged through a photo-electric cell at a rate directly proportional to the intensity of the light falling thereon from a radio-

graphic image appearing on a light sensitive surface after passage of X-rays through an object on to said surface, and automatically operable to cause energization of one of the relays of said control means with an attendant cessation of the operation of said X-ray tube energizing means when the radiographic image reaches a predetermined density; safety timer means automatically operable to cause a cessation in the operation of said X-ray tube energizing means after the lapse of a preselected period of time in the event said intensity responsive means fails to operate to terminate the X-ray exposure, and an indicator operable in response to the operation of said safety timer means to apprise the operator that the safety timer means and not the intensity responsive means terminated the X-ray exposure.

10. A phototimer for automatically controlling energization of an X-ray tube to consistently produce radiographic images of uniform density regardless of variations in object thicknesses or varying exposure times comprising energizing means for said X-ray tube, control means responsive to initiation by an operator adapted to automatically cause operation of said X-ray tube energizing means including a plurality of relays whose contacts normally close a partial circuit to said control means, protective means including a substantially constant voltage power supply and a relay energizable therefrom and operable to partially complete a circuit to the windings of the relays of said control means and serving in event of power supply failure to prevent operation of said control means with otherwise attendant possible injury to the X-ray tube, intensity responsive means including a circuit having a capacitor therein adapted to be charged through a photoelectric cell at a rate directly proportional to the intensity of the light falling thereon from a radiographic image appearing on a light sensitive surface after passage of X-rays through an object on to said surface, and automatically operable to cause energization of one of the relays of said control means with an attendant cessation of the operation of said X-ray tube energizing means when the radiographic image reaches a predetermined density; an impedance element connected to said capacitor subject to a voltage inversely variable with the time of energization of said X-ray tube and operable to compensate for the time delay required for said X-ray tube energizing means to cease operation in response to operation of said intensity responsive means to prevent an over-exposure and assure density uniformity of the radiographic image, safety timer means automatically operable to cause a cessation in the operation of said X-ray tube energizing means after the lapse of a preselected period of time in the event said intensity responsive means fails to operate to terminate the X-ray exposure, and an indicator operable in response to the operation of said safety timer means to apprise the

15

operator that the safety timer means and not the intensity responsive means terminated the X-ray exposure.

11. A phototimer for automatically controlling energization of an X-ray tube to consistently produce radiographic images of uniform density regardless of variations in object thicknesses or varying exposure times comprising a light tight hood provided with a fluorescent screen at one end thereof and a camera at its other end for photographing images appearing on said fluorescent screen, means for supporting a film carrying cassette at the end of the hood adjacent said fluorescent screen, energizing means for said X-ray tube, intensity responsive means automatically operable to cause a cessation in the operation of said X-ray tube energizing means when the radiographic image produced by passage of X-rays through an object on to said fluorescent screen or film reaches a predetermined density, and means for shielding said camera during the making of a radiographic exposure on the film within said cassette and operable upon movement of said means to change the adjustment of said intensity responsive means.

20. 12. A phototimer for automatically controlling energization of an X-ray tube to consistently produce radiographic images of uniform density regardless of variations in object thicknesses or varying exposure times comprising a light tight hood provided with a fluorescent screen at one end thereof and a camera at its other end for photographing images appearing on said fluorescent screen, means for supporting a film carrying cassette at the end of the hood adjacent said fluorescent screen, energizing means for said X-ray tube, intensity responsive means automatically operable to cause a cessation in the operation of said X-ray tube energizing means when the radiographic image produced by passage of X-rays through an object on to said fluorescent screen or film reaches a predetermined density, and a shutter in said hood movable into a position to shield said camera when a radiographic exposure on the film within said cassette is desired and operable to adjust the setting of said intensity responsive means as said shutter is moved to its various positions.
